CLAIM

The ornamental design for a fire pit, as shown and described.

DESCRIPTION

FIG. 1 is a top, front, right side perspective view of a fire pit, showing the claimed design;

FIG. 2 is a front elevation view thereof, wherein the rear elevation view, the left side elevation view, and the right side elevation view are identical to the view shown in FIG. 2;

FIG. 3 is a top plan view thereof;

FIG. 4 is a bottom plan view thereof;

FIG. 5 is a bottom, rear, left side perspective view thereof; and,

FIG. 6 is a top, front, left side perspective view thereof. The dashed broken lines in the drawing depict portions of the fire pit that form no part of the claimed design.
